Primary Examiner — David Muller*Assistant Examiner* — Nathan Johnston(74) *Attorney, Agent, or Firm* — Eric Karich; Karich & Associates(57) **CLAIM**

The ornamental design for a “ceramic vaporizer,” as shown and described.

DESCRIPTION

FIG. 1 is a perspective view of a ceramic vaporizer, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing of various recesses of the ceramic vaporizer as shown in FIG. 7 are included for the purpose of illustrating environmental structure and form no part of the claimed design.
